CLAIM

The ornamental design for a plant pots and tray combination, as shown and described.

DESCRIPTION

FIG. 1 is a perspective view of a plant pots and tray combination showing our new design;

FIG. 2 is a top plan view thereof;

FIG. 3 is a bottom plan view thereof;

FIG. 4 is a front elevational view thereof, the rear elevational view thereof being identical thereto;

FIG. 5 is a left side elevational view thereof, the right side elevational view thereof being identical thereto;

FIG. 6 is an exploded perspective view thereof;

FIG. 7 is a top plan view of the tray portion;

FIG. 8 is a front elevational of one of the pots;

FIG. 9 is a left side elevational of one of the pots; and,

FIG. 10 is a bottom plan view of one of the pots.
